UNITED STATES PATENT OFFICE.

ALEXANDER HOKANSON, OF BURNSIDE, CONNECTICUT, ASSIGNOR TO THE CARLING TOOL & MACHINE COMPANY, OF HARTFORD, CONNECTICUT, A CORPORATION OF CONNECTICUT.

BRUSH.

Application filed December 17, 1921. Serial No. 523,159.

To all whom it may concern:

Be it known that I, ALEXANDER HOKANSON, a citizen of the United States, residing at Burnside, in the county of Hartford and 5 State of Connecticut, have invented certain new and useful Improvements in Brushes, of which the following is a specification.

This invention relates to brushes of that type wherein bristles secured between suitable lengths of twisted wire are deflected into desirable brush form by a suitable member comprising a handle or back which engages the bristles to confine them on one side of the core formed by the twisted wires.

15 In the drawings accompanying and forming part of the present specification I have shown in detail preferred forms of embodiment of my invention, which to enable those skilled in the art to practice the same will be 20 fully set forth in the following description while the novelty of the invention is defined in the claims succeeding said description.

In the drawings.—

Figure 1, is a perspective view of a brush 25 constructed in accordance with my invention.

Figure 2, is a similar view of a modified form of brush, certain parts being broken away to more clearly show the construction.

Figure 3, is a detail perspective view of a 30 brush member.

Figure 4, is a detail perspective view of a handle member, and

Figures 5, 6, 7 and 8 are diagrammatic transverse sectional views illustrating the 35 method of assembling a brush member and a handle member.

Referring to the drawings the numeral 3, designates a brush holding member developed from sheet metal of suitable thickness 40 to permit of a flat blank being formed therefrom and bent into desired shape by forming dies. The brush receiving part 4, of the member 3, is substantially U-shaped in transverse section and is extended at one end with 45 shortened sides to form a part 5, of handle 6, the mating part 7, of which is secured thereto by rivets 8. At the ends of the brush receiving channel of the part 4, lugs 9, are bent inwardly from the U-shaped sides for 50 a purpose that will hereinafter more clearly appear. The brush member, see Fig. 3, is composed of bristles 10, held between twisted wires 11, which normally form a central core about which the bristles extend in cylindrical arrangement, such construction be-

ing well known in the brush making art. It will be understood however, that when a brush member is associated with a holder 3, the cylindrical form of the brush material is changed by confining the bristles in the manner about to be disclosed.

Referring to Figs. 5, 6, 7 and 8, the method of assembling the holder and brush members will now be described attention being first directed to the fact that the sides of the holder previous to receiving the brush are spread apart as shown in Fig. 4. Taking a suitable length of brush material the bristles are parted longitudinally and folded as indicated by the arrows in Fig. 5, to extend as shown in Fig. 6, so that the part surrounding the wire core may be introduced between the sides of the holder, see Fig. 7. The sides of the holder are then bent inwardly to firmly engage the bristles, see Fig. 8, thereby holding them in a flat brush relation, the base of the bristles being so constricted about the wire core as to form a compact mass within the channel of the holder and affording an effective grip for the latter. Adjacent the ends of the brush member the holder is provided with lugs 9, already mentioned, which close the ends of the channel and prevent endwise movement of the brush member therein. Attention is also directed to the fact that the sides of the U-shaped holder are flared outwardly to thereby prevent the edges thereof bearing against the bristles in an injurious manner.

The modified form of brush shown in Fig. 2, differs from the construction described, in that a rib 13, is secured as by bolts 14, to the holder 15, thereby forming two channels to receive duplicate brush members 16 and 17, it being obvious that this arrangement is employed when a heavier thicker brush is desired.

While I have described specific embodiments of my invention it will be understood that it is not limited to the exact construction shown but may be varied in many respects as to detail without departure from the scope of the invention as defined by the appended claims.

Having thus described my invention, what I claim and desire to protect by Letters Patent is,—

1. A holder for a brush including two concave members united with their edges in substantial coincidence to form a rounded

handle, one of the members being extended beyond the handle portion and provided with lateral flanges for engaging a brush element of the character described, said flanges converging above a plane defined by the mating edges of the handle portion and then diverging to form convexly curved opposed surfaces for gripping the brush therebetween substantially in the manner set forth.

2. A holder for a brush including two concave members united with their edges in substantial coincidence to form a rounded handle, one of the members being extended

beyond the handle portion and provided 15 with lateral flanges for engaging a brush element of the character described, said flanges converging above a plane defined by the mating edges of the handle portion and then diverging to form convexly curved opposed surfaces for gripping the brush therebetween, the ends of the flanges comprising inwardly turned lugs to engage the ends of the brush member substantially in the manner set forth.

In testimony whereof I affix my signature.

ALEXANDER HOKANSON.
